UNITED STATES PATENT OFFICE.

JAMES G. CUTLER, OF ROCHESTER, NEW YORK.

MAIL-BOX.

SPECIFICATION forming part of Letters Patent No. 519,057, dated May 1, 1894.

Application filed December 23, 1891. Serial No. 415,989. (No model.)

To all whom it may concern:

Be it known that I, JAMES G. CUTLER, a citizen of the United States, residing at Rochester, in the county of Monroe, in the State 5 of New York, have invented an Improved Mail-Box, of which the following is a specification, reference being had to the accompanying drawings.

My invention relates to certain improvements in the construction of mail-boxes, which improvements are fully described and illustrated in the following specification and the accompanying drawings,—the novel features thereof being specified in the claims annexed 15 to the said specification.

In the accompanying drawings, representing a mail-box embodying my improvements, Figure 1 is a front elevation. Fig. 2 is a vertical section on the line 2—2, Fig. 1. Fig. 3 20 is a horizontal section on the line 3—3, Fig. 1. Fig. 4 is a partial side-view of the swinging-box. Fig. 5 is a plan view of the same.

In the mail-box represented in the accompanying drawings, A is the outer casing, 25 which is closed at the top by the head or cover C, and open at the lower end to permit the movement of the inner mail-receptacle or holder B, which slides lengthwise or downward to the requisite degree out of the box, 30 as indicated at B', to permit the removal of the mail-matter through an opening J in its front or side. An orifice b in the outer case, closed by the swinging flap L, permits the introduction of mail-matter into the box. 35 The box is locked by securing the inner mail-holder in the outer case by means of the hasp and staple, F H, and any ordinary fastening device such as the padlock I.

It is designed to make the whole structure 40 of sheet-metal, thereby securing strength, lightness and cheapness. In this case the outer shell A is bent into shape and formed with a riveted joint e, Figs. 2 and 3. The head C is flanged and riveted, as shown. The 45 upper edge of the inner holder is beaded or bent outward as represented at a, Fig. 2, and the lower edge of the outer case is beaded or bent inward, as shown at c, so as to prevent the inner holder from slipping or being drawn 50 entirely out of the box. In the assembling of the parts of the box, the head C is first

riveted in, and then, the inner holder B, provided with the flange a, but without its lower head D, is inserted in the case, the flange c is then formed on the case, and, the holder 55 being then withdrawn a sufficient distance from the case, the head D is attached by flanging or riveting as may be preferred,—the opening J permitting access to the interior of the holder for this purpose. It will 60 be observed that the holder is somewhat smaller than the interior of the case and one or more springs, R, are employed in this space to press the holder against the front of the case, and prevent a thin letter or postal card 65 from sticking in the joint around the edges of the opening J. These springs are secured to the holder on its rear side, near its upper end, and bear against the interior of the case. They also serve by the friction they cause to 70 retard the downward movement of the holder.

In order to provide for attaching the box to a post P, or other suitable support, by a device having fastenings concealed within the case, I employ the space between the 75 holder and case, or a recess formed by bending the case outward, as shown at N, Figs. 2 and 3, to receive the nut f, on the end of a suitable rod, strap or band, O, which sustains the box in any desired position. 80

Access may be had to the nut, or other suitable fastening device, through the opening J, while the holder is withdrawn sufficiently from the case. The head D may be provided with the handle E. It will be observed that 85 the opening J does not extend entirely down to the head D, but that a wall K projects upward from the head a suitable distance, serving to prevent the mail-matter from falling 90 out of the box when opened.

In Figs. 4 and 5 I have represented a modified manner of supporting a mail-box, on a pivot at its upper end, so that it can be swung into the horizontal or nearly horizontal position, for convenience of access to the 95 contents.

Y, Figs. 4 and 5, is an arm projecting outward from any suitable support, and carrying the pivot U, to which the box is attached by means of the arm T and disk U. In order 100 to provide for holding the box in an approximately horizontal position, I form a notch in

the disk U, in which a pin or catch on the spring V engages, to hold the box in the position A' if desired. The spring may also be employed to secure the box in the vertical 5 position.

I claim—

1. The combination, in a mail box, of the outer case A, permanently closed at its upper end, and having mailing orifice b, and the inner sliding holder B closed at its lower end and provided with opening J on the side next the mailing orifice, and means for preventing the entire withdrawal of the holder from the case, substantially as described.
- 15 2. The combination, with the outer case A having head C, inwardly turned flange c at its lower end, and mail-orifice b, of the inner sliding holder B having flange a and opening J on the side next the mail-orifice, said opening J being normally in direct communication with the mail-orifice and adapted to be exposed by lowering the sliding holder B, substantially as set forth.
- 25 3. The combination in a mail box of the outer case closed at one end and the inner holder arranged to slide within the case and provided with an opening adapted to receive the mail when the box is closed and to expose it when the box is open, and a fastening 30 for said case concealed by the inner holder

when closed, said holder being adapted to be suspended from the case, substantially as set forth.

4. The combination, in a mail box, of an outer case closed at its upper end, an inner 35 sliding holder provided with an opening on one side, means for supporting the holder from the case when in its lowest position, and a spring arranged within the case and adapted to keep the holder on its apertured side in 40 contact with the interior of the holder, substantially as described.

5. A swinging mail-box pivoted at or near its upper end, and provided with means for securing it in an approximately horizontal 45 position, for convenience of access to its contents, substantially as described.

6. The combination, with a swinging mail-box, consisting of an outer case and an inner sliding holder, of means for securing it in an 50 approximately horizontal position, substantially as described.

7. The combination, with the mail-box A, of the arm Y carrying spring V, the pivot X and notched disk U, substantially as de- 55 scribed.

JAMES G. CUTLER.
